(57) **CLAIM**

The ornamental design for the “abutment for a dental implant”, as shown and described.

DESCRIPTION

FIG. 1 is a bottom plan view of an abutment for a dental implant showing our new design;

FIG. 2 is a top perspective view thereof;

FIG. 3 is a front elevation thereof;

FIG. 4 is a left side elevation thereof, the side opposite being a mirror image;

FIG. 5 is a rear elevation thereof; and,

FIG. 6 is a bottom perspective view thereof; and,

FIG. 7 is a top plan view thereof.
